(57) **CLAIM**

The ornamental design for a display panel portion with a computer icon, as shown and described.

DESCRIPTION

The sole FIGURE is a front view of a display panel portion with a computer icon, showing an image of our new design. The broken lines showing a portion of a display panel are included for the purpose of illustrating portions of the article and form no part of the claimed design. The outermost solid lines in the FIGURE represent a portion of the display panel which forms part of the claimed design.
